BY Carl P. Gelpel

ATTORNEY

UNITED STATES PATENT OFFICE.

ARTHUR SALZER, OF NEW YORK, N. Y.

DESIGN FOR A LAMP-GLOBE.

53,049.

Specification for Design.

Patented Mar. 4, 1919.

Application filed October 12, 1918. Serial No. 257,886. Term of patent 3½ years.

To all whom it may concern:

Be it known that I, ARTHUR SALZER, a citizen of the United States, and resident of the borough of Manhattan, in the city, county, and State of New York, have invented a new, original, and ornamental Design for Lamp-Globes, of which the following is a specification, reference being had to the accompanying drawing, forming part thereof.

Figure 1 is a front view of a lamp globe, showing my new design;

Fig. 2 is a side view of the same; and

Fig. 3 is a bottom plan view thereof.

I claim:

The ornamental design for a lamp globe, as shown.

ARTHUR SALZER.
